UNITED STATES PATENT OFFICE.

BENJAMIN R. BRESLER, OF BRIDGEPORT, CONNECTICUT.

WASTE-VALVE-OPERATING MECHANISM.

Application filed July 5, 1927. Serial No. 203,340.

The present invention relates to waste valve operating mechanism and has for an object the provision of means whereby the waste or drain valve of a bath tub, wash basin, lavatory or the like may be alternately opened and closed by simply pushing a hand piece.

A further object is to provide a simplified and sturdy mechanism for carrying out the above object and in which the only part of the mechanism disposed above the tub, basin or the like is the hand piece which is pushed to open the valve and pushed to close the same.

An additional object is to provide a mechanism as above described with means for restoring the hand piece to its original position after each operation.

Other objects and advantages will become apparent from a consideration of the following description taken in connection with the accompanying drawing wherein:—

Fig. 1 is a vertical sectional view showing the operating mechanism in its relation to the drain valve;

Fig. 2 is an elevation showing the hand piece and parts directly associated therewith;

Fig. 3 is a detail sectional view showing the operating cam in its relation to the valve stem; and

Fig. 4 is a detailed view looking from the bottom, showing the clutch means for imparting a quarter turn to the cam on each manipulation of the hand piece.

Referring in detail to the drawing, 5 indicates a wash basin which is provided with a drain opening 6 and an overflow opening 7. Arranged in the drain opening 6, is a bushing 8 flanged at its upper end as at 9 and threaded at its lower end into a fitting 10. The bushing 8 secures the fitting 10 to the under side of the wash basin and has secured to its lower end a drain pipe 13.

Within the bushing 8 is the valve including a head 11 arranged to fit on the flange 9 of the bushing for closing the drain. A spider 12 forms part of the valve and guides the same to insure proper seating of the head 11. On the lower end of the valve there is adjustably fitted a threaded stud 13 for a purpose to be described.

Mounted in the flange 14 of the wash basin is a tubular sleeve 15 through which slidably extends a vertically disposed rod 16 having its upper end threaded into a

metal bushing 17 embedded in a hand piece 18 of porcelain or the like. Within the sleeve 15 and about the rod 16 is a coil spring 19. This spring bears at one end 60 against the bottom of the sleeve and at its upper end bears against the hand piece 18. The spring serves to restore and maintain the parts in their normal position as seen in Fig. 1.

Threadably connected to the lower end of rod 16, for adjustment is a yoke 20, a jam nut 21 being provided to secure the parts in their adjusted position. In its lower portion the yoke is provided with a vertical slot 70 22 and a horizontal slot 23.

The fitting 10 has a tubular extension 24 provided with bearings 25 and 26 for a shaft 27. One end of shaft 27 projects into fitting 10 and fixed to this end of the shaft is a cam 28. Cam 28 has a projection at each side of the shaft so that on one complete rotation of the shaft the valve will be twice raised and lowered owing to the fact that the stud 13 remains always in contact with 80 the cam.

Mounted on the outer end of the shaft is a collar 29 fixed to the shaft as with a pin. The centrally grooved portion of collar 29 is received within the vertical slot 22 of the yoke to act as a guide but to permit free vertical movement of the yoke.

Likewise mounted on shaft 27 to turn therewith is one element 30 of a clutch element, the other element 31 of which is mounted on the shaft for movement relative thereto. Element 31 is hollow and a coil spring 32 arranged therein presses at its respective ends against the collar 29 and the element to maintain the elements 30 and 31 95 in engagement.

A projection 33 on the element 31 carries a pin 34 which operates in the horizontal slot 23 in the yoke 20. To maintain the element 30 in position, a spring pressed plunger 35 is arranged to engage in notches 36 in said element.

In the operation of the device, assuming the parts to be in the position shown in Fig. 1, and it being desired to open the valve, it is but necessary to push downwardly on the hand piece 18. Such action results in a downward movement being given the yoke 20 and owing to the pin and slot connection between the yoke and element 31 such element is given a quarter turn. Any turning movement thus delivered

causes a corresponding movement to be delivered to element 30 and thence to shaft 27 resulting in a quarter turn being given cam 28 to elevate the valve.

5 Plunger 35 acts to maintain the element 30 in its new position and this results in the valve being maintained open. However spring 19 returns the hand piece, yoke, and element 31 to their former position the arrangement of teeth on the clutch elements and the spring 32 permitting this.

10 When it is desired to again close the valve it is but necessary to push the hand piece to give a quarter turn to the cam moving 15 the same to let the valve descend to closed position.

Having thus described the invention what is claimed is:

1. Means for operating a valve, said 20 means including a hand piece, a shaft, a cam on said shaft and in contact with said valve, a rod connected with said hand piece, a yoke adjustably connected with said rod, means for maintaining said hand piece and 25 rod in normal position, a clutch on said shaft and comprising a pair of complementary members one of which is secured to and the other of which is turnable relative to the shaft, means normally maintain-

ing said elements in clutching engagement, 30 means for maintaining said shaft against casual movement, and a pin and slot connection between the yoke and turnable clutch element whereby partial turning movements may be imparted to said clutch element on depressing said hand piece and a step-by-step turning movement imparted to the shaft to open and close the valve. 35

2. Means for operating a valve, said means including a hand piece, a shaft, a 40 cam on the shaft, and in contact with the valve, a clutch on said shaft and comprising a pair of complementary members one of which is secured to and the other of which is turnable relative to the shaft, means 45 normally maintaining said elements in clutching engagement, means engaging one of said elements and maintaining the shaft against casual movement and means for imparting a partial turn to said clutch elements 50 and through them to the shaft and cam to open and close the valve on repeated depressing of the hand piece.

Signed at Bridgeport in the county of Fairfield and State of Connecticut this 30th 55 day of June, A. D., 1927.

BENJAMIN R. BRESLER.
